(57) **CLAIM**

The ornamental design for a removable user interface module for an uninterruptible power supply, as shown and described.

DESCRIPTION

FIG. 1 is a perspective view of a removable user interface module for an uninterruptible power supply design including an exemplary LCD display below the upper surface of the module;

FIG. 2 is a top plan view thereof, including an exemplary LCD display below the upper surface of the module;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.

The broken lines showing portions of the removable user interface module for an uninterruptible power supply designs in FIGS. 1-7 are for illustrative purposes only and form no part of the claimed design.
